CABINET FOR DATA PROCESSING EQUIPMENT OR SIMILAR ARTICLE

Paul O. Rawson, Trumbull, Conn., assignor, by mesne
assignments, to Digital Equipment Corporation, May-
nard, Mass.

Filed Mar. 12, 1965, Ser. No. 84,221

Term of patent 14 years

(Cl. D26—5)

F I G. I

FIG. 2

FIG. 3

FIG. 4

FIG. 5

FIG. 1 is a front perspective view of a cabinet for data processing equipment or similar article embodying my new design;

FIG. 2 is a rear view thereof;

FIG. 3 is a bottom view thereof;

FIG. 4 is a side view thereof; and

FIG. 5 is a top view thereof.

The dominant features of my design reside in the full line showing of the two side-by-side vertical rectangular cabinet sections juxtaposed on the third coextensive horizontal rectangular cabinet section, the vertical sections being separated from the horizontal section by the pronounced horizontal band and from each other by the pronounced vertical band, the intersection of the two bands being centered directly above the third section so as to give the overall impression of squatness and compactness.

I claim:

The ornamental design for a cabinet for data processing equipment or similar article, substantially as shown and described.
